UNITED STATES PATENT OFFICE.

HOMER WORDEN, OF NEW YORK, N. Y.

DESIGN FOR A BOTTLE-CASE.

SPECIFICATION forming part of Design No. 16,188, dated July 28, 1885.

Application filed December 26, 1884. Term of patent 7 years.

To all whom it may concern:

Be it known that I, HOMER WORDEN, a citizen of the United States, residing in the city, county, and State of New York, have invented or produced a new and original Design 5 for a Bottle-Case, of which the following is a specification.

Figure 1 of the accompanying drawings is a side view of a bottle-case embodying my 10 design, and Fig. 2 is a vertical transverse mid-section thereof.

The body A of the case is cylindrical, with a dome-shaped top, B, above which is a cylindrical head, C. The top B and head C constitute 15 the cover of the case. The body A has a rounded bead, a, at its bottom, and a bead, b, is located on the cover at the junction of the cylindrical body with the dome-shaped top B. The head C has a bead, c, at its top, 20 and also a bead, d, at its base where it joins the top B.

The essential features of the design are the cylindrical body, the dome-shaped top, the cylindrical head, and the four beads a, b, c, and d. 25

I claim—

The design for a bottle case herein shown and described, the same consisting of a cylindrical body A, dome-shaped top B, cylindrical head C, bead a at the bottom of the body, bead b at the junction of the body and cover, bead c at the top of the cylindrical head, and bead d at the junction of the cylindrical head and dome-shaped top. 30

In testimony that I claim the foregoing as 35 my invention I have signed my name, in presence of two witnesses, this 12th day of December, 1884.

HOMER WORDEN.
